UNITED STATES PATENT OFFICE

WILLIAM F. HAFNER, OF CHICAGO, ILLINOIS, ASSIGNOR TO HAFNER MANUFACTURING COMPANY, OF CHICAGO, ILLINOIS, A CORPORATION OF ILLINOIS

TOY VEHICLE

Application filed June 12, 1931. Serial No. 543,855.

This invention relates to a toy vehicle, but more particularly to a toy vehicle which is driven by a spring motor and which is adapted to travel over toy tracks. The main objects of the invention are, to provide means for attracting attention to the vehicle when it is traveling; to provide such means which will more or less simulate a device ordinarily associated with the full-sized or working embodiment of the vehicle simulated in the toy, and to provide means for guarding against unwinding of the spring motor and possible disengagement of the ends of the spring from the parts to which they are normally connected by reverse movement of the vehicle.

In the present instance, the specific object of my invention is to provide means for ringing a bell carried by a toy locomotive. Other objects and advantages of the invention will be understood by reference to the following specification and accompanying drawing in which I have illustrated my invention as applied to a toy locomotive.

25 In the drawing:

Figure 1 is a side elevation, certain parts being broken away and illustrated in section, and

Figure 2 is an end elevation of the rear end 30 of the locomotive.

Referring now to the drawing, I have illustrated a toy locomotive 5 which embodies a simulation of the general features of a full-sized working locomotive, the extent to which the simulated features are copied from a full-sized locomotive being variable to suit the particular class of trade for which the vehicle is intended. The toy locomotive is illustrated as including a spring motor 6 suitably secured to the body of the locomotive and having driving wheels 7 which are adapted to fit the toy tracks 8—8 which are connected by means of ties 9 in any suitable, well known or conventional manner.

45 As clearly shown in Figure 1, a bell 10 is secured as indicated at 11 to the under side of a floor member 12 which constitutes part of the cab portion of the locomotive. A clapper 13, in this instance, in the form of a bell 50 crank having arms 14 and 15, is pivoted, as

indicated at 16, to the rear end of the frame of the spring motor 6. The outer end of the bell-crank arm 14 is provided with an enlargement or head 17 which is adapted to strike the bell to ring the same, and the arm 55 15 of the bell crank extends downwardly and rearwardly from the pivot 16, as clearly shown in Figure 1. The length of the arm 15 may be such that it will drag on the floor or surface on which the tracks 8 are disposed, 60 as indicated at 18, and, obviously, if desired, the arm may be somewhat shortened so that it will clear the floor. However, the arm 15 should be long enough to engage the ties 9 as an incident to forward movement of the 65 locomotive. Obviously, when the locomotive travels fast enough over the tracks, the successive engagements between the arm 15 and the successive ties 9 will impart a kick to the bell-crank clapper 13 which will cause the 70 clapper to repeatedly ring the bell 10.

By inspection of the drawing, it will be seen that the clapper 13 is limited in its pivotal movement in a clockwise direction (Figure 1) by engagement of the arm 15 with the rear 75 end of the frame of the spring motor to which the clapper is pivoted. By reason of its limited pivotal movement, rearward movement of the locomotive will be resisted, inasmuch as the arm 15 will necessarily tend to 80 swing in a counterclockwise direction by reason of its frictional engagement with the floor, as indicated at 18, or by reason of its engagement, with one of the ties 9. Hence, the arm 15 constitutes a device for resisting 85 rearward movement of the locomotive. In spring-motor-driven vehicles, this is a desirable feature, since there is always some danger that the springs might be disconnected from the shafts or other parts to which they 90 are normally connected if the mechanism be forced to travel in a reverse direction beyond a certain limit.

In some instances, it may be desirable to provide means for disabling the clapper. 95 Such means may be of any suitable form, and, in this instance, is indicated as consisting of a clip 19 which is pivoted, as at 20, to the rear end of the frame of the motor. As indicated in broken lines in Figure 1, the 100

clapper 13 may be swung to its up position and the clip 19 turned on its pivot so as to hold the clapper in said up position. When so positioned, the clapper is disabled and the 5 ringing of the bell will be eliminated.

While I have described my invention as applied to a toy locomotive, it is obvious that it is applicable to other vehicles; wherefore, I do not wish to be limited to the described structure. Changes may be made in the above described structure without departing from the spirit of my invention, the scope of which should be determined by reference to the following claims, the same being construed as broadly as possible consistent with the state of the art.

I claim as my invention:

1. In a toy vehicle, the combination of a bell mounted on the vehicle, a clapper for 20 ringing said bell, said clapper comprising a bell crank having means at the end of one arm for striking said bell, said bell crank being pivoted to the vehicle on an axis extending transversely of the direction of travel of the vehicle and having its other arm extending downwardly so as to engage obstructions in its path of travel, whereby the clapper is actuated as an incident to the travel of the vehicle.
2. The combination of a toy locomotive, tracks over which the locomotive is adapted to travel, ties connecting said tracks, sound-producing means carried by said locomotive comprising a bell, a clapper for sounding the bell, and means carried by the clapper for engaging said ties so as to be thereby actuated as an incident to travel of the locomotive over the tracks.
3. The combination of a toy locomotive, 40 tracks over which the locomotive is adapted to travel, ties connecting said tracks, and sound-producing means carried by said locomotive comprising a bell, a clapper for sounding the bell comprising a bell crank pivoted intermediate its ends to the locomotive, one arm of said bell crank having means at its outer end for engaging the bell to sound the same, and the other arm depending from said pivot and being adapted to engage 50 said ties so as to actuate the clapper as an incident to travel of the locomotive over the tracks.
4. The combination of a toy locomotive, tracks over which the locomotive is adapted 55 to travel, ties connecting said tracks, and sound-producing means carried by said locomotive comprising a bell, a clapper for sounding the bell, means carried by the clapper for engaging said ties so as to be thereby actuated as an incident to travel of the locomotive over the tracks, and means for disabling said clapper.
5. In a toy vehicle, the combination of a device for producing a predetermined effect for attracting attention to the vehicle, means

for actuating said device comprising a member carried by the vehicle and secured thereto for movement relative thereto in a direction substantially parallel to the direction of travel of the vehicle, said member having 70 a portion adapted to engage an obstacle in its path of travel so as to be thereby actuated as an incident to the travel of the vehicle, and means for disabling said member.

6. The combination of a toy vehicle, a bell 75 carried by said vehicle, a clapper also carried by the vehicle for sounding the bell, a pair of tracks over which the vehicle is adapted to travel, means extending between said tracks and having a part adapted to engage 80 a portion of the clapper to actuate the same as an incident to travel of the vehicle over said tracks.
